ART OF REFRIGERATION

Harry Sloan, Ernst S. H. Baars, and Charles G. Bach, Milwaukee, Wis., assignors to The Vilter Manufacturing Company, Milwaukee, Wis., a corporation of Wisconsin

Application September 22, 1930
Serial No. 483,526

10 Claims. (Cl. 62—115)

This invention relates in general to improvements in the art of refrigeration, and relates more specifically to improvements in the construction of refrigerating apparatus and in the mode of operating refrigerating systems especially for the purpose of obtaining quick freezing of the product treated.

Generally stated, an object of the invention is to provide improvements in the art of refrigeration whereby more efficient and economical cooling may be effected under various conditions of operation.

Some of the more specific objects of the invention may be enumerated as follows:

15 To provide an improved quick freezing or low temperature refrigeration system which is simple in construction and efficient in operation.

20 To provide an improved low temperature refrigerator which is operable with greater economy in power consumption than has heretofore been possible in such devices.

25 To provide an improved system of refrigeration which is capable of maintaining extremely low freezing temperatures of approximately 60° to 70° Fahrenheit below zero, within the cooling coils of the system.

30 To provide an improved quick freezing refrigeration system which may be readily operated in conjunction with existing refrigerating systems.

35 To provide an improved refrigerating system of the direct expansion type, wherein the evaporating surface is utilized to its fullest extent, thus insuring more efficient operation of the system.

40 To provide improved instrumentalities for furnishing a proper supply of liquid refrigerant at sufficiently high pressure to the liquid distributing headers of a refrigerating system, so as to permit satisfactory regulation of the flow of refrigerant from the headers.

45 To provide improved means for maintaining the entire evaporating surfaces of a refrigerating system supplied with an abundant quantity of liquid refrigerant.

50 To provide a low temperature refrigerating system in which a compressor of relatively small capacity may be effectively utilized, thereby reducing to a minimum the power consumption.

To provide improved means for removing oil and water from the fluent refrigerant employed in a refrigerating system.

55 To provide improved emergency devices for maintaining a refrigerating system in operation upon failure of a portion of the system to function properly.

To provide improved cooling apparatus for systems wherein the refrigeration requirements are variable throughout the freezing period.

To provide improved means for defrosting the cooling coils of a refrigerator without materially interfering with the normal operation thereof, and without undesirably raising the temperature within the cooling zone.

To provide improved means for facilitating refrigeration of objects of various shapes and forms.

To provide an improved mode of maintaining objects in frozen condition for a maximum period of time.

These and other objects and advantages will appear from the following detailed description.

A clear conception of embodiments of the various novel features and of the improved mode of constructing and of operating refrigerating apparatus built in accordance with the invention, may be had by referring to the drawings accompanying and forming a part of this specification, in which like reference characters designate the same or similar parts in the several views:

Fig. 1 is a diagram of an improved quick freezing refrigeration system embodying the invention, and of improved means for defrosting the cooling coils of the system;

Fig. 2 is an enlarged section through one of the special fittings employed in the improved quick freezing system;

Fig. 3 is a transverse vertical section through a typical cooling room especially adapted for use in connection with the quick freezing refrigeration system;

Fig. 4 is a perspective view of an improved form of material supporting racks showing the same assembled for use in supporting relatively large objects; and

Fig. 5 is a similar perspective view of several of the improved racks showing the same assembled for use in connection with relatively flat objects.

The improved quick freezing refrigeration system specifically illustrated in diagrammatic form in Fig. 1 of the drawings, comprises in general a primary or ordinary refrigerating unit, and a secondary or low temperature refrigerating unit adapted to receive its supply of liquid refrigerant from a relatively low temperature portion of the primary refrigerating unit, the secondary unit also being adapted to return the said refrigerant in gaseous condition to the primary unit at a temperature corresponding to that of the source of gaseous refrigerant supply in said primary unit.

The primary or ordinary unit includes a high pressure compressor 13 having an inlet pipe 53 communicating with the gas collecting chamber of a high pressure accumulator 16, the compressor 5 also having a discharge pipe 37 directed into the inlet end of a condenser 14, and into a defrosting connection 35 having a control valve 36 therein which is normally closed. A cooling water supply pan 54 is adapted to deliver cooling liquid such as water over the tubes of the condenser 14 to cool the gas discharged from the compressor 13 and finally condense it to a liquid which then flows from the condenser 14 to the receiver 15 through a header and connection 68. The outlet 10 of the receiver 15 communicates with a pipe 55 having a pressure regulating and reducing valve 56 therein, the pipe 55 being adapted to deliver liquid refrigerant into the lower portion of the supply of liquid refrigerant within the accumulator 16. A pipe 47 communicates with the pipe 55 at the high pressure side of the regulating valve 56, this pipe 47 having a control valve 62 therein and serving to conduct liquid refrigerant from the receiver 15 to an oil separator and cooler 41, the function of which will be later described. Another pipe 31 having a control valve 57 therein, is adapted to conduct liquid refrigerant at relatively high pressure from the receiver 15 to the inlet or supply pipe 48 of the secondary system, for purposes which will be later explained. The entrained gas contained within the liquid refrigerant delivered into the lower portion of the accumulator 16 through the pipe 55, bubbles upwardly through the refrigerant in the accumulator and eventually mixes with the gas in the collecting chamber at the upper end of the accumulator, from which the compressor 13 receives its supply. A liquid refrigerant withdrawal pipe 58 which is adapted for interchangeable connection with the supply pipe 48 of the secondary unit, either through a circulating pump 30 or through a valve controlled by-pass 43, also communicates with the accumulator 16 below the level of the liquid therein, and a refrigerant return pipe 46 leading from the separator and cooler 41, communicates with the upper end of the accumulator 16 above said liquid level. The lower portion of the accumulator 16 additionally communicates through a relatively large connection 50 with the lower part of the high temperature evaporator 17, the upper part of which communicates through a relatively large return connection 45 with the gas collecting chamber at the upper end of the accumulator 16. The evaporator 17 is of usual construction, being provided with the ordinary means for transferring heat from the brine to the refrigerant which passes through the evaporator 17 from the inlet connection 44 to the outlet connection 45. The secondary or low temperature unit includes a low pressure compressor 11 of relatively small capacity, having an inlet pipe 59 communicating with the upper gas collecting chamber of a low pressure accumulator 19, the compressor also having a delivery pipe 60 directed into a discharge gas cooler 26, the delivery pipe 61 of which communicates with the separator and cooler 41. The separator and cooler 41 serves to reduce the temperature of the gaseous refrigerant delivered through the pipe 61, to that of the gases in the collecting chamber at the upper end of the accumulator 16, before the gaseous refrigerant is delivered to the return pipe 46. This result is accomplished by utilizing refrigerant from the receiver 15 and passing the same through the pipe 47 and valve 62 into the cooler 41 and causing the same to intermingle with the gaseous refrigerant passing from the cooler 26 through the cooler 41. The secondary refrigerating unit, moreover, has one or more evaporating coils 12, each of which receives its supply of liquid refrigerant from two headers 27, 21 and delivers gas and surplus liquid refrigerant to a suction header 63 past a flow control valve 64. The first supply header 27 normally receives liquid refrigerant at relatively low temperature from the lower portion of the accumulator 16, through the pipes 58, 48, the latter of which is provided with shut-off valves 65, 66 and is adapted to deliver the low temperature refrigerant past control valves 18 and through ejector fittings 39 to the individual coils 12. The supply header 27 is, however, also adapted to receive liquid refrigerant at relatively high pressure, direct from the receiver 15 past the valve 57 and through the supply pipes 31, 48. The second supply header 21 normally receives liquid refrigerant from the low pressure receiver 19 through a circulating pump 20 and through the pipe 29 past a shut-off valve 38, and is adapted to deliver refrigerant past regulating valves 22 into the ejector fittings 39. Each of the ejector fittings 39, the details of which are shown in Fig. 2, is so constructed that the liquid refrigerant delivered thereto from the pipe 48 under relatively high pressure, will flow at high velocity across the annular gap which communicates directly with the supply header 21 containing liquid refrigerant at low pressure. The high velocity jet thus formed ejects liquid refrigerant from the header 21, and the mixture is delivered as a spray or in partially vaporized condition into the evaporators, and is deposited over the entire heat transfer surfaces of the coils 12, instead of being deposited only at the lower part of the pipes thus wetting only a small part of their inner surfaces. A valve controlled by-pass 40 is also provided between the pipes 29, 48 for permitting delivery of liquid refrigerant from the accumulator 19 directly into the header 27 through the supply pipe 48. It is desirable that the liquid refrigerant be admitted to the upper end of the coils 12, as indicated in Fig. 1, in order to permit free evaporation of the downwardly advancing refrigerant, as well as to permit ready drainage of the coils. The suction header 63 communicates through a pipe 28 with the gas collecting chamber of the accumulator 19, and this collecting chamber also communicates through the pipe 59 with the suction side of the compressor 11. The lower portion of the accumulator 19 has an oil separating trap 67 associated therewith, this trap being in communication with an oil drum 23 past a valve 25. The upper portion of the drum 23 is communicable through a valve 24 with the gas collecting chamber of the accumulator 19 and has a blow-off valve 42 associated with the lower portion thereof. By opening the valves 24, 25, the accumulated oil may be drained from the trap 67 into the drum 23, whereupon the valves 24, 25 may be closed and the valve 42 opened to effect removal of the oil from the drum 23 by virtue of the expansion of the entrapped expansible refrigerant within the upper portion of the drum 23. While the defrosting connection 35 may be utilized occasionally to admit high pressure gas at relatively high temperature to the coils 12, by opening the valve 36 and closing the valves 18, 38 and simultaneously retaining the valves 22 open, this method of completely defrosting the

evaporator of the secondary unit, should only be utilized at relatively rare intervals, as for instance semi-annually. In addition to complete defrostation it is desirable, in order to maintain the system in most effective operating condition, to 5 additionally defrost the coils 12 at frequent intervals and without interfering with the normal operation of the unit. This may be accomplished with the aid of the defrosting device shown in Fig. 1, which comprises a compressed air header 32, flexible hoses 33 communicating with the header 32, and valve controlled nozzles 34 for suddenly releasing compressed air against the surfaces of the coils 12 in the form of jets. The 10 jets thus delivered against the coils serve to remove loose frost crystals from the coils 12, and the sudden expansion of the compressed air upon release thereof from the nozzles 34, produces a cooling effect and avoids undesirable heating of 15 the coils 12 and of the cooling rooms 68.

Although the objects treated are of variable form and especially variable thickness, it is desirable to expose all portions of these objects to the cooling atmosphere and to provide a supporting 20 structure which may be quickly adjusted to support a maximum number of the objects regardless of their shape, within a cooling room 68 of fixed dimensions. In order to accomplish this result, special supporting racks shown in detail in Figs. 25 4 and 5 are provided. Each of these racks comprises longitudinally extending slats 49 and transverse intermediate supports 50 of rectangular cross-section. By piling the slats 49 and supports 50 as specifically shown in Fig. 4, relatively thick 30 objects such as hams 51 may be piled upon the upper slats and between the successive layers of slats. By piling the slats 49 and supports 50 as shown in Fig. 5, relatively flat objects such as bacon sides 52 may be piled upon the upper slats 35 and between the successive layers of slats. By tipping the intermediate supports 50 on their sides, the successive layers of slats 49 may be brought even closer together, thereby providing an extremely flexible supporting structure which is 40 capable of supporting a maximum number of objects of various shapes within a given space. The entire structure remains within the cooling room 68, and the adjustment for the purpose of 45 accommodating objects of various sizes and shapes may be quickly effected.

During normal operation of the refrigerating system specifically illustrated in Fig. 1, the compressor 13 of the primary unit is operated to withdraw gas through the pipe 53 from the accumulator 16 and to expel highly compressed gaseous refrigerant, usually ammonia, through the discharge pipe 37 to the condenser 14. In passing through the condenser 14, this highly compressed gas having relatively high initial temperature is 50 cooled and simultaneously condensed by the cooling fluid delivered from the tray 54 and the relatively cool liquid refrigerant is delivered to the receiver 15. When the valve 57 is closed, the refrigerant from the receiver 15 is discharged 55 through the pressure reducing valve 55 into the accumulator 16 and entrained gases are expelled upwardly through the liquid refrigerant in this accumulator and mingle with the gases collected at the upper end of the accumulator to await return to the compressor 13 with other gases discharged into this collecting chamber. Some of the liquid refrigerant passes from the accumulator 16 through the connection 44 to the evaporator 17, wherein the refrigerant is gasified and 60 is eventually returned through the connection 45

to the gas collecting chamber in the upper end of the accumulator 16. If the pressure within the accumulator 16 is sufficiently high, the pump 30 is not being operated and the valve in the by-pass 43 is open, the valve 65 in the pipe 48 also being open. Liquid refrigerant then passes from the accumulator 16 through the pipe 58, by-pass 43 and pipe 48 to the header 27, the valve 66 also being open. From the header 27 the liquid refrigerant at relatively low temperature but at relatively high pressure, is delivered through the regulating valves 18 and ejector fittings 39 to the evaporator coils 12.

Simultaneously with this delivery of liquid refrigerant through the ejector fittings 39, additional liquid refrigerant is delivered from the header 21 through the ejector fittings, as previously explained, this additional refrigerant being forced through the pipe 29 and open valve 38 by means of the pump 20 communicating with the low pressure accumulator 19. An abundant supply of liquid refrigerant is therefore insured in each of the coils 12, and the ejector fittings 39 serve to spray the liquid ammonia thus admitted, into the coils 12 and thus insure proper coating 100 of the heat transferring surfaces with refrigerant. The gases and surplus refrigerant delivered from the coils 12 passes through the valves 64 into the suction header 63 from which the mixture is delivered into the low pressure accumulator 19. 105 The gases which collect in the upper portion of the accumulator 19 are withdrawn through the pipe 59 by the booster compressor 11, and are discharged by this compressor into the ammonia discharge gas cooler 26 from which they are subsequently discharged, through the pipe 61, cooler 41 and pipe 46 to the pressure accumulator 16 of the primary unit.

If the pressure within the accumulator is insufficient to force the liquid refrigerant through the 115 pipe 58, by-pass 43, and pipe 48, to the coils 12, then the valve in the by-pass 43 may be closed and the emergency pump 30 may be placed in operation to withdraw the refrigerant from the accumulator 16 and to positively force the same through 120 the header 27 and ejector fittings 39 to the coils 12. It may also be desirable to utilize the liquid refrigerant directly from the receiver 15 in the secondary unit, and this may be done by opening the valve 57 in the pipe line 31, and by closing the 125 valve 65 in the pipe line 48. Under certain conditions, as when the low pressure accumulator becomes over supplied with liquid, it may be desirable to inject the excess liquid into the pipe 48 in advance of the ejector fittings 39. This may 130 be done by adjusting the regulating valves 22 and opening the valve in the by-pass 40, to produce an increased pressure in the pipe 29 so that the excess liquid refrigerant will be forced into the pipe 48 and subsequently will pass through the 135 header 27 and the ejector fittings 39. The operation of the cooler 41, oil expelling drum 23 and of the defrosting device, will be readily apparent from the foregoing description.

It will be apparent that the improved system 140 provides a highly economical association of elements for producing quick freezing of materials. By virtue of the fact that the secondary refrigerating unit utilizes refrigerant derived from a relatively low temperature portion of the primary unit, an enormous reduction in temperature within the coils 12 of the secondary unit is made possible. By utilizing the high pressure accumulator of the primary unit as a source of supply, a relatively small quantity of refrigerant is required in 145 150

the secondary unit to perform the desired function, and the booster compressor 11 of the secondary unit may be of relatively small capacity and hence utilizes comparatively little power. The 5 improved system abounds with safety devices whereby the secondary unit may be maintained in operating condition even if the primary unit should fail, and the various by-passes, pumps and auxiliary connections permit an operator to obtain 10 practically any desired condition of operation of the secondary unit. The improved ejector fittings not only insure an abundant supply of refrigerant for the coils 12, but also produce effective distribution of the refrigerant within 15 the coils, and the defrosting devices and improved supporting racks also enhance the effectiveness of the unit to a maximum and permit efficient treatment of the materials which are to be frozen. It should be moreover understood that the diagrammatic illustration of hand valves, is not to be considered as a limitation, since it is also contemplated to utilize automatic valves wherever desirable.

It should be understood that it is not desired to 25 limit this invention to the exact details of construction and to the precise mode of operating refrigerating systems, herein shown and described, for various modifications within the scope of the appended claims may occur to persons 30 skilled in the art.

It is claimed and desired to secure by Letters Patent:

1. In combination, a primary refrigerating unit including a high pressure accumulator, a secondary refrigerating unit comprising an evaporator the inlet of which is adapted to receive refrigerant from a relatively low temperature portion of said high pressure accumulator, a low pressure accumulator communicating with the discharge of 40 said evaporator, and means for delivering additional refrigerant from said low pressure accumulator to said inlet.

2. In combination, a high pressure accumulator, a low pressure evaporator, a low pressure accumulator 45 communicating with the discharge of said evaporator, means for supplying refrigerant at relatively low temperature from said high pressure accumulator to the inlet of said evaporator, and means for supplying additional refrigerant 50 from said low pressure accumulator to said first mentioned supply means.

3. In combination, an evaporator, a primary refrigerating unit for supplying a quantity of high pressure refrigerant to said evaporator, a 55 low pressure accumulator for receiving liquid and gaseous refrigerant from said evaporator, a compressor for returning the gaseous portion of said refrigerant to said primary unit, and means for returning the liquid portion of said refrigerant 60 to said evaporator.

4. In combination, an evaporator, a primary refrigerating unit comprising a receiver and a high pressure accumulator, means for establishing a pressure difference in said receiver and said 65 accumulator, and means for effecting interchangeable delivery of refrigerant from said receiver or from said accumulator to said evaporator.

5. In combination, a low temperature evaporator, a high pressure accumulator, means for

conducting liquid refrigerant from a low temperature portion of said accumulator to said evaporator, a by-pass in said conducting means for normally effecting direct delivery of refrigerant through said conducting means by the higher pressure existing in said accumulator, and a pump for positively urging refrigerant through 80 said conducting means when said pressure is insufficient.

6. In combination, a primary refrigerating unit including a high pressure accumulator and a high pressure compressor, a secondary refrigerating unit comprising a low pressure evaporator and a low pressure accumulator, means for normally delivering refrigerant from said high pressure accumulator to said evaporator and from said evaporator to said low pressure accumulator, and means for interchangeably delivering refrigerant from said compressor directly to said 85 evaporator.

7. In combination, a primary refrigerating unit and a secondary refrigerating unit, each of said units comprising an evaporator, an accumulator, a compressor, and a receiver, means for conducting refrigerant from the accumulator of said primary unit to the evaporator of said secondary unit, and means for conducting refrigerant from the receiver of said secondary unit to the receiver of said primary unit.

8. In combination, primary and secondary refrigerating units each comprising an evaporator, an accumulator, a compressor, and a receiver, means for conducting refrigerant from the accumulator of said primary unit to the evaporator of said secondary unit, means for conducting refrigerant from the accumulator of said secondary unit to the compressor of said secondary unit, and means including the receiver of said secondary unit for conducting refrigerant from the compressor of said secondary unit to the accumulator 105 of said primary unit.

9. In combination, primary and secondary refrigerating units each comprising an evaporator, an accumulator, a compressor, and a receiver, means for conducting refrigerant from the accumulator of said primary unit to the evaporator of said secondary unit, means for conducting refrigerant from the evaporator of said secondary unit through the accumulator and compressor and receiver of said unit to the accumulator of 110 said primary unit, and means for conducting refrigerant from the accumulator of said primary unit to the evaporator and to the compressor of said unit.

10. In combination, primary and secondary refrigerating units each comprising an evaporator, an accumulator, a compressor, and a receiver, means for conducting refrigerant from the accumulator of said primary unit to the evaporator of said secondary unit, means for conducting refrigerant from the evaporator of said secondary unit through the accumulator and compressor and receiver of said unit to the accumulator of said primary unit, and means for conducting refrigerant from the compressor of said primary unit to the evaporator of said secondary unit.
